UNITED STATES PATENT OFFICE.

FRANK L. WRIGHT, OF CHICAGO, ILLINOIS, ASSIGNOR TO THE LUXFER PRISM PATENTS COMPANY, OF SAME PLACE.

DESIGN FOR A PRISM-PLATE.

SPECIFICATION forming part of **Design No. 27,996**, dated December 7, 1897.

Application filed October 21, 1897. Serial No. 655,973. Term of patent 14 years.

To all whom it may concern:

Be it known that I, FRANK L. WRIGHT, a citizen of the United States, residing at Chicago, in the county of Cook and State of Illinois, have invented a certain new and original Design for Prism-Plates, of which the following is a description.

My invention relates to designs for prism-plates.

10 Figure 1 is a plan view of a prism-plate embodying my design. Fig. 2 is a cross-section therethrough on line 2 2.

15 A is the body of the plate; B B, a series of surface areas thereon formed by the lines of separation C C. The surface areas are substantially uniform. D D are lines produced upon such surface areas, so as to form on a group of central surface areas a central design, as is shown.

The essential features of my design are 20 found in a prism-plate comprising a substantially flat extended body with prisms on one side and lines of separation on the other which divide such side into a series of substantially uniform surface areas and a pattern produced 25 upon a group of such surface areas near the center of the plate, so as to give the appearance of an ornamented center with a surrounding field.

I claim—

30 A design for a prism-plate, substantially as shown and described.

FRANK L. WRIGHT.
